HEAD COVER

Dorothy Lester and Andrew Lester,
Hobe Sound, Fla.

Application December 5, 1945, Serial No. 632,903

4 Claims. (Cl. 2-174)

1

The present invention relates to a novel and improved head cover, in the form of a hood to be temporarily worn by women, and the obvious purpose of the invention is that of a combined shield and protector serving to prevent the soiling of garments and dresses, and further serving to prevent derangement of the wearer's hair and facial make-up.

As the preceding general statement of the invention implies, we are aware that the art to which the invention relates is characterized by many and varied forms of helmets, so-called head and face protector caps, hoods and the like. In general, all of these protectors and shields are constructed of flexible transparent sheet material, such as for example Cellophane, Pliofilm or equivalent stock. They usually slip and fit over the head, face and neck and envelop same in a manner to provide the desired shielding and protecting facilities and results.

It is common knowledge that when a dress is slipped over one's head, hair-dos and facial makeup are often deranged, causing considerable inconvenience and exasperation. Hence, it has become common practice to wear hoods in retail clothing stores, in the home, and in the theatre and elsewhere to prevent soiling of women's dresses when they are being tried on and to prevent same from coming into contact with the hair and face.

In carrying out the principles of the present invention we have evolved and produced a simple and economical, pliable bag, this with the thought in mind of achieving the desired ends in a more effective and satisfactory and simple manner.

An outstanding object of the invention is to provide a hood in the form of a simple bag which is preferably ventilated, is snug fitting due to the particular shape adopted, comfortable and characterized by the incorporation of features and facilities which promote eye-appeal and reduced costs of manufacture and sale.

More specifically, we have adopted and used a simple and inexpensive bag functioning as a protector and shield, the same being especially shaped at the mouth portion to accommodate quick operable fastening means, whereby to expedite the steps of applying and removing.

Novelty is also predicated, as will be later seen, on simple and expedient fastening means such as causes the mouth of the bag to conform to the anatomy and thus insure more effective and practical results.

From a more specific standpoint, novelty is also predicated upon the use of open-ended hemps or

2

pockets on front and rear panels of the bag-like hood, these serving as pockets for drawstrings. The drawstrings are arranged and anchored on predetermined portions of the panel and at predetermined ends of the pockets to provide satisfactory means for drawing and gathering the mouth of the hood, the adaptation being such that coacting end portions of the drawstrings are in slidably riding contact in order to apply the pulling strain on the string-ends, this in a manner to minimize the likelihood of tearing adjacent areas and regions of the tearable stock from which the hood is, in practice, made.

In the accompanying drawings, wherein like numerals are employed to designate like parts throughout the views:

Figure 1 is a side elevational view showing the hood in use and the profile of the wearer.

Figure 2 is a view like Figure 1 but showing the additional step of fastening the mouth portion of the bag or hood around the neck of the wearer.

Figure 3 is a plan or elevational view of the bag or hood, shown in Figures 1 and 2, in flat ready-to-use form.

Figure 4 is a view similar to Figure 3 but showing a modification illustrating a different shape and a different fastening means.

Figure 5 is a front elevation of the form of the bag shown in Figure 4 but illustrating the same in use.

Figure 6 is an enlarged cross-section taken on the plane of the line 6-6 of Figure 3, looking in the direction of the arrows.

Figure 7 is a similar section, this being on the plane of the line 7-7 of Figure 4.

Figure 8 is an enlarged detail section on the plane of the line 8-8 of Figure 4 looking in the direction of the arrows.

Figure 9 is a fragmentary side elevational view showing a different type of tying and fastening means.

Figure 10 is also a fragmentary side elevational view showing a still further type of fastening device or means.

The various bags shown are fundamentally and generically the same in broad construction.

Attention is first invited to Figures 1 to 3 inclusive in which the numeral 12 designates, as a unit, the hood forming bag. It is made up of a front panel 13 and a complementary rear panel 14 these of somewhat ovate configuration in marginal outline as shown to advantage in Figure 3. The marginal edges of the respective front and rear panels 13 and 14 are brought together and secured by a binder 15 or seal as brought out to

advantage in Figure 6. The lower end portion of the panel 13 is provided with a substantially sector-shaped extension which may be perhaps best defined and visualized as an apron 16.

The fastening means in this instance comprises an elastic element 17 secured at spaced points by way of tabs 18 to the exterior lower end portion of the back or rear panel 14. On one end of the elastic is an eye 19 to accommodate a quick attachable and releasable hook 20. It follows that when the bag is placed in hood-like fashion over the head and face of the wearer it assumes the position first seen in Figure 1. Then, the ends of the elastic are brought together and fastened by the hook 20 and eye 19 respectively, thus gathering the surrounded portion of the bag around the neck of the wearer. The length and shape of the apron 16 is such as to insure effective maintenance of the bag, once the fastening devices 19 and 20 are secured together.

In such instances, if desired, either one or both panels may be provided with a plurality of apertures 21, these for ventilating purposes.

The modified bag shown in Figures 4 and 5 is differentiated and denoted by the numeral 22. Here again I employ front and rear panels 23 and 24, the marginal edges thereof being heat treated and thus sealed together, as brought out to advantage at 25 in Figure 7. The crown portion of the bag in this instance is straight across as indicated at 26 in Figure 4, with the adjacent edge portions slanting down as at 27 and merging into straight vertical edge portions 28 as both panels are the same in shape and the aforementioned apron is omitted.

Attention is now directed to Figures 4, 5 and 8 in which we illustrate and comprehend unique drawstrings for effectively and adequately gathering the mouth of the bag 22. To begin with, the lower ends of the front and rear panels 23 and 24 are formed with inverted V-notches and the bottom edges are then doubled upon themselves to define open-ended front and rear hem 29 and 30 usable as drawstring pockets. A draw-string 32 is threaded to work slidably through said front pocket 29; the left-hand end thereof (Figures 4 and 5) emerging from the adjacent or corresponding end of said pocket 30 and its terminal is glued or otherwise securely fastened, as at 34, to the rear panel 24 in alignment with the rear pocket-end 30. Also, the anchored end portion 31 stretches across and "bridges" the adjacent V-notch 31, as indicated at 35. The opposite or right-hand end of said drawstring extends through and beyond the corresponding end of said front-pocket 29, denoted at 32a, this for convenient grasping and pulling purposes. The other drawstring 33 is threaded and runs slidably in the rear pocket 30; the right-hand end thereof being glued or otherwise securely attached and anchored, as at 36, to the corresponding end of the front panel 23. The attached end portion 36 stretches across and thus bridges the V-notch 31 and the opposite free end 33a extends out through and beyond the left-hand end of the rear pocket 30, where it can be grasped for pulling and mouth gathering purposes. The respective free ends 32a and 33a emerge from the pockets 29 and 30 by way of said V-notches 31 and are thus situated to bind and ride slidably against the bridging portions 35 and 37, respectively. Thus, by using said "bridges," when the two free ends 32a and 33a are simultaneously grasped and "yanked" out and then down, the pulling strains and stresses are absorbed by said "bridges," whereby to

strengthen the arrangement and to prevent tearing of the notched bag-ends and/or ends of said pockets 29 and 30. It goes without saying that these special adaptations are appreciable structural improvements in drawstring constructions.

In Figure 9 the bag is differentiated by the numeral 38 and is made up of front and rear panels 39 and 40 with the lower portion of the panel 39 provided with a depending apron 41. The difference of this form of the invention is in the tie or fastening means. That is to say, the tie strings are "stitched" or sealed around the lower end portion of the rear panel 40 as indicated at 42 and the terminal ends are left free flying, as it were, to extend sufficiently, as indicated at the points 43 and 44, to permit said ends to be brought together and tied in a manner to gather the apron and entire mouth of the bag around the neck of the wearer.

The bag in Figure 10 is denoted by the numeral 45 and comprises panels 46 and 47 marginally seamed, as in 48, the panel 46 having a depending apron 49. In this form the fastening means comprises a pair of tabs 50 with their adjacent free ends secured separately together by an appropriate snap-fastener 51. In practice the anchored ends of the tabs are simply glued or secured by a suitable adhesive to the lower edge portion of the rear panel 47. The tabs are comparatively short and when secured together they draw or pull the portion 52 rather tightly around the back of the neck, to the size of the neck. When the snap fastener is secured as shown in the drawing, the apron is tucked underneath the chin and gathered sufficiently to maintain the bag, as a unit, effectively in place.

Attention is at this point directed to certain features and advantages which attend the invention, to wit:

From the standpoint of health, it will protect the wearer due to contagious diseases from dresses coming in direct contact with wearers' nose and mouth. Thus, common colds, venereal diseases, skin diseases, trench mouth, hair and scalp diseases such as dandruff, falling hair and hair lice are guarded against and prevented.

Use of the hood will save money which would otherwise be lost by retailers having to mark down dresses soiled with lipstick, rouge, mascara and face powder. Also the likelihood of tearage, especially lace or net dresses and trimmings, from coming in contact with bobbie pins, hair pins, hair ornaments, earrings and eyeglasses is appreciably minimized. Then too, since dresses slide off and on much more easily and quickly, there is not much danger of tearing a dress from tugging and pulling either on or off. What is more, use of my hood saves time and patience for salesgirl and customer alike. The above advantages can be equally appreciated by the in a home user in every day use.

For the store customer or home user, the hood protects makeup and hair-do and minimizes wasting time and effort rearranging hair and re-touching facial makeup. The wearer does not have to remove hair ornaments such as flowers or large combs or the like. Furthermore, the wearer may keep eyeglasses on inasmuch as the hood eliminates the danger of catching glasses on the dress and also protects wearer's face from being scratched by buttons, hooks, zippers, and the like.

In addition, our head-cover will be a boon to a wearer allergic to woolens, dress goods, and closet odors; will help protect wearer from sun

rays if the material used is properly made and tinted; will afford a wearer protection from ill effects of wind, such as chapping of face or lips, watering of the eyes, and will also guard against blowing sand or dust; and, if made of water-proof material, it can be used to protect women's hair-dos and make-up in shower bath and employed for use in rainy or stormy weather.

As before indicated novelty is predicated on the one hand on the bag, regardless of the fastening devices, on the other hand on the combination of the bag and fastening devices, and further on the fastening means individually.

We desire to stress the fact that similarly constructed and utilized prior patented bags, hoods and shields usually have the seams so that it extends longitudinally across the crown of the head the seam being in alignment with the profile of the wearer. In the instant invention the bag is just in reverse. That is to say, the marginal seam is at right angles to the face of the wearer as brought out to advantage in Figures 1, 2, 5, 9 and 10. This means that the front panel covers the face and the rear panel covers the top and back of the head of the wearer. A bag thus constructed is better fitting and more aptly fulfills the requirements of an article of this type. This is particularly so taking into consideration the advantages derived from the apron and the relatively short back panel, said features co-acting in assuring better conformation of the features to the anatomy of the wearer.

This article is also valuable to store operators who use mannequins as it protects the wig and greatly facilitates the dressing and undressing of the mannequins, in addition, it affords protection to said wigs from dust, light, and disarrangement when said mannequins are stored away.

Finally, the invention also has other uses which need not necessarily be stressed herein.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

We claim:

1. A head covering of the class described comprising a bag embodying front and rear edge seam connected panels having inverted V-shaped notches adjacent the opposite lower ends of the seams, said lower end portions of said panels having horizontal open-ended pockets, and separate drawstrings running slidably through the respective pockets, the free ends of the strings being adapted to be pulled in opposing directions, the

opposite ends of said drawstrings being anchored on opposite panels and end portions of the mouth of said bag.

2. A temporary slip-over head and face helmet of the class described comprising a transparent open-mouthed bag embodying marginally connected front and rear panels provided with notches situated at opposite ends of said open mouth, the lower ends of said panels having opposed, substantially parallel open-ended hems forming front and rear drawstring pockets, a drawstring threaded and running slidably through said front pocket, the left-hand end of said drawstring emerging from the adjacent pocket-end and being attached to the corresponding end portion of said rear panel, the right-hand end being free for finger-grasping, pulling and gathering purposes, and a second draw-string threaded and running slidably through said rear pocket, the right-hand end of the latter drawstring emerging from the corresponding pocket-end and being securely attached to the adjacent end of the front panel, and the left-hand end of said second-named drawstring extending beyond the adjacent end of said rear pocket and likewise being free for grasping, pulling and gathering purposes.

3. The structure defined in claim 2, the respective attached ends of said drawstrings bridging the coacting notches.

4. The structure defined in claim 2, the respective attached ends of said drawstrings bridging the coacting notches, and the free ends of said drawstring being slidably contactable with said bridging portions to facilitate the procedure of pulling said drawstrings in a manner to gather the mouth and pockets without tearing and disrupting the open ends of said pockets.
